(57) **CLAIM**

The ornamental design for a tool for cleaning an espresso machine drip tray, as shown and described.

DESCRIPTION

1. Tool for cleaning an espresso machine drip tray
1.1 is a front perspective view of a tool for cleaning an espresso machine drip tray showing my new design;
1.2 is a front view thereof;
1.3 is a back view thereof;
1.4 is a left-side view thereof;
1.5 is a right-side view thereof;
1.6 is a top view thereof;
1.7 is a bottom view thereof; and
1.8 is a bottom perspective view thereof.

In the reproductions, the portions of the reproductions shown in broken lines form no part of the claimed design.
